RAILWAY TRAFFIC CONTROLLING APPARATUS

Filed Sept. 15, 1924

UNITED STATES PATENT OFFICE

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed September 15, 1934. Serial No. 737,741.

My invention relates to railway traffic controlling apparatus, and particularly to apparatus of the type wherein governing mechanism carried on a vehicle is controlled by energy received from the trackway. More specifically my present invention relates to the vehicle-carried portion of such apparatus.

I will describe one form of apparatus embodying my invention, and will then point out the novel features thereof in claims.

The accompanying drawing is a diagrammatic view showing one form of apparatus embodying my invention.

Referring to the drawing, the reference character V designates a railway vehicle, such as a locomotive, designed to travel on the track rails 1 and 1^a of a railway. Mounted in front of the forward axle of the vehicle V is a core 9 of magnetizable material carrying a receiving coil 11 arranged in inductive relation to the track rail 1. This core 9 also carries two receiving coils 12 and 13 mounted in inductive relation to the track rail 1^a. The three coils 11, 12 and 13 which are mounted on the core 9 I will term the "front" receiving coils. Also mounted on the vehicle in the rear of the rear axle is a second magnetizable core 10 carrying two receiving coils 14 and 15 each arranged in inductive relation to the track rail 1. The core 10 carries a third receiving coil 16 arranged in inductive relation to the track rail 1^a. The three coils 14, 15 and 16 which are carried on the rear core 10 I will term the "rear" receiving coils.

The front and rear receiving coils are arranged to receive energy inductively from the track rails due to alternating currents flowing in these rails. Referring to the section of track K—L, formed by insulated joints 2 in the rails, track circuit current is supplied to the rails by a transformer 3, the secondary of which is connected across the rails at the exit end of the section, whereas a second alternating current, which I will term the "local" current, is supplied to the track rails by a transformer 4, the secondary of which is connected with the middle points of two resistances 6 connected across the rails

at the entrance and exit ends of the section, respectively. The currents supplied to the rails by the transformers 3 and 4 are of the same frequency but differ in phase, and a pole-changer 5 is associated with one of these 55 transformers, whereby the polarity of one current with respect to the other may be reversed. It will be noted that the track circuit current supplied by the transformer 3 flows in opposite directions in the two track 60 rails at any given instant, whereas the local current supplied by the transformer 4 flows in the same direction in the two track rails at any given instant. The circuits shown in the drawing for supplying these two currents to the track rails are purely diagrammatic and of the simplest possible type; it is understood that in actual practice one or both of the circuits for supplying these currents will be controlled by apparatus not 65 shown in the drawing.

As will appear hereinafter, the vehicle V is provided with apparatus for cutting out the vehicle governing mechanism when the vehicle is passing through non-positive control territory, that is, territory not provided with the trackway circuits illustrated in section K—L. In order to operate the cut-out apparatus on the vehicle, means are provided at the entrance to such territory for supplying a greater amount of energy to the vehicle than is supplied by the local transformer 4. One such trackway cut-out means is shown in section L—N, wherein local current is supplied to the rails by a transformer 8 the primary of which is connected with the same source of alternating current as the primary of transformer 4. Transformer 8 however, has a higher voltage secondary than transformer 4, so that the local current in the rails 90 of section L—N is greater in value than the local current supplied to the track rails of section K—L by the transformer 4.

The vehicle V is provided with a normal track receiving circuit which passes from a 95 track condenser C^T, through wire 17, contact 18 of a circuit controller S, wires 19 and 20, coil 12, wire 21, coil 11, and wires 22, 23 and 24 to the track condenser C^T. This circuit includes the two front receiving coils 11 and 100

12 connected in opposition, that is, connected in such manner that the voltages created in these two coils by track circuit current flowing in opposite directions in the track rails are 5 additive.

The vehicle is also provided with a normal local receiving circuit which passes from a local condenser C^L , through wire 32, contact 93 of circuit controller S, wire 33, coil 14, 10 wire 26, coil 16, wires 27, 23, 24, 31, 30, 64 and 29, resistance R, and wire 28 to condenser C^T . This circuit includes the two coils 14 and 16 connected in series, that is, connected in such manner that the voltages induced therein by 15 local current flowing in the same direction in the two track rails are additive.

The two normal receiving circuits, just traced in detail, include contacts of a circuit controller S. This circuit controller S is 20 preferably operated automatically by the reversing gear of a vehicle in such manner that when the vehicle is running forward the contacts 18 and 93 are in the positions in which they are shown in the drawing, wherein the 25 normal receiving circuits traced above are closed. When the vehicle is proceeding backwardly the contacts 18 and 93 of circuit controller S are reversed; the normal receiving circuits are then opened and reverse receiving circuits are closed which circuits are as follows:

The reverse track receiving circuit is from condenser C^T , through wire 17, contact 18 of circuit controller S, wire 25, coil 15, wire 26, 35 coil 16, and wires 27, 23 and 24 to condenser C^T . This circuit includes the two rear coils 15 and 16 connected in opposition so that the voltages induced in these coils by track circuit current are additive.

40 The reverse local receiving circuit is from condenser C^L , through wire 32, contact 93 of circuit controller S, wire 34, coil 13, wire 21, coil 11, wires 22, 23, 24, 31, 30, 64 and 29, resistance R, and wire 28 to condenser C^L . 45 This circuit includes the two front coils 11 and 13 connected in series so that the voltages induced in these coils by local current in the track rails are additive. The resistance R included in the normal and in the reverse local 50 receiving circuits is normally short circuited by a branch circuit which passes from the lower terminal of resistance R through wire 36, normally closed contact 37 of a manually operable circuit controller E and wire 35 to the 55 upper terminal of resistance R.

It will be noted from the foregoing that when the vehicle V is moving forward a pair of front coils are so connected as to create voltage across condenser C^T due to track circuit current supplied to the rails by transformer 3, whereas a pair of rear coils are connected to create voltage across condenser C^L due to local current supplied to the track rails by transformer 4. When the vehicle is moving backward, however, so that the track cir-

cuit current is shunted from the front receiving coils by the wheels and axles of the vehicle, a pair of rear receiving coils are connected in such manner as to create voltage across condenser C^T due to the track circuit current, whereas a pair of front receiving coils are so connected to create voltage across condenser C^L due to the local current in the track rails. One important feature of my invention is the provision of only two sets of coils located in the front and rear respectively of the vehicle, and circuit controlling apparatus so arranged that these two sets of coils serve as track receiving coils and local receiving coils respectively for either direction of movement of the vehicle. 70 75 80

Another feature of my invention is the provision of but one condenser C^T for tuning either pair of coils 11-12 or 15-16 to resonance according as one pair or the other is serving as the track receiving coils, and a single condenser C^L for tuning either pair of coils 11-13 or 14-16 according as one of these pairs or the other is serving as the local receiving coils. It may sometimes be found in practice, however, that no two receiving coils will be exactly alike, that is, no two coils will have exactly the same inductance. In order to compensate for different inductances, auxiliary condensers may be connected 90 across the terminals of any coil or any pair of coils, as may be found necessary. For example, if the front track receiving coils require more capacity than the rear track receiving coils, a condenser 94 may be connected 100 across wires 20 and 23, and if the rear local receiving coils require more capacity than the front local receiving coils, a condenser 95 may be connected across wires 33 and 23. 105

The vehicle is provided with a main relay A, which, as here shown, is of the induction motor type, comprising two stator windings 43 and 44 and a rotor 45 controlling a series of contacts 48, 49, 50 and 51. The stator winding 43 is tuned to resonance at the frequency of the trackway currents by a condenser 46, and the sta or winding 44 is tuned to resonance at the same frequency by a condenser 47. Winding 43, which I will term the "track" winding, is supplied with energy under the control of the track receiving circuits, whereas winding 44, which I will term the "local" winding, is supplied with energy under the control of the local receiving circuits. The control of the energy to the two windings of relay A is preferably accomplished through the medium of amplifiers B^T and B^L . Amplifier B^T , which may be termed the "track" amplifier, is provided with an input circuit controlled by the voltage across the track condenser C^T , which circuit comprises wires 38, 96 and 31; whereas amplifier B^L is provided with an input circuit controlled by the voltage across condenser C^L , which circuit com- 115 120 125 130

prises wires 28, 35, 37, 36, 29, 64, 30, 97 and 39. The output circuit of amplifier B^T is through wire 40, winding 43, wire 42, armature 53^G, wires 64, 30 and 96 to amplifier B^T , whereas the output circuit for amplifier B^L is through wire 41, winding 44, wire 42, armature 53^G, wires 64, 30 and 97 to amplifier B^L . When the vehicle V occupies a section of track which is supplied with both track circuit current and local current of normal relative polarity, both windings of relay A will be energized, and the contacts of this relay will then be swung to the right. When the vehicle occupies a section of track which is supplied with track circuit current of normal relative polarity and local current of reverse relative polarity, both windings of relay A will be energized but the contacts of this relay will then be swung to the left. When the supply of either track circuit current or local current is discontinued, relay A will be de-energized so that the contacts will occupy their vertical or intermediate positions.

The supply of energy for operating the vehicle-carried apparatus is obtained from a pair of wires 58 and 64 which are connected with a suitable source of direct current, not shown in the drawing. This source may, for example, be the standard 32-volt headlight generator now used on many locomotives. The current for the amplifiers B^T and B^L is obtained from a dynamotor D comprising a generator 53^G of relatively high voltage, such as 350 volts, and a motor 53^M connected across the supply line 58—64.

The governing elements on the vehicle are a cab signal G and a pair of brake governing magnets H and M. The cab signal G comprises three lamps 54^L, 54^M and 54^H, adapted when lighted to indicate "low speed", "medium speed", and "high speed", respectively. The magnets H and M govern suitable brake controlling mechanism in such manner that when magnet H is energized the vehicle can proceed at a given high speed without incurring an automatic brake application, whereas when magnet H is de-energized and magnet M is energized, an automatic application will be incurred if the vehicle exceeds a given intermediate speed limit. When both brake magnets H and M are de-energized, a brake application will occur if the vehicle exceeds a given low speed limit.

When the main relay A is energized in normal direction, a circuit is closed which passes from wire 58, through the right-hand point of contact 48 of relay A, wires 59, 60 and 61, lamp 54^H of signal G, wires 62 and 63, and right-hand point of contact 49 of relay A, to wire 64. At the same time the high speed magnet H is energized by a circuit which passes from wire 58, through the right-hand point of contact 48, wires 59 and 65, back point of contact 67 of a relay F, wire 69, magnet H, wire 70, back point of contact 68

of relay F, wires 71, 72 and 63, and the right-hand point of contact 49 to wire 64. High speed lamp 54^H and high speed magnet H are then both energized, so that the vehicle may proceed at full speed without incurring an automatic application of the brakes. When relay A is energized in reverse direction the intermediate speed lamp 54^M is energized by a circuit which passes from wire 58, through the left-hand point of contact 48 of relay A, wires 73 and 74, lamp 54^M, wires 75 and 76, and the left-hand point of contact 49 of relay A, to wire 64. At the same time the intermediate speed magnet M is energized by a circuit which passes from wire 58, through the left-hand point of contact 48, wires 73 and 77, magnet M, wires 78 and 76, and the left-hand point of contact 49, to wire 64. The vehicle may then proceed at intermediate speed without incurring an automatic brake application. When relay A is de-energized, the low speed lamp 54^L is lighted by a circuit which passes from wire 58, through wire 79, back contact 50 of relay A, wires 80 and 81, back point of contact 66 of relay F, wire 82, lamp 54^L, wire 83, back contact 51 of relay A, and wire 84 to wire 64. Both magnets H and M are then de-energized, so that an automatic brake application will be incurred if the vehicle exceeds a given low speed.

It will, of course, be apparent from the foregoing that when the vehicle enters non-positive control territory it will be restricted to low speed unless means are provided for cutting out the automatic controlling apparatus under this condition. As stated hereinbefore, a special section L—N is located at the entrance to such territory for supplying the train with local current of greater value than the local current supplied by transformer 4. The value of resistance R is such that if this resistance is not shunted when the vehicle is receiving the normal trackway local current, relay A will become de-energized, but that when the vehicle is receiving the greater amount of local current furnished by the special section, relay A will remain energized even though the shunt around resistance R is opened at contact 37. The normally closed contact 37 and the normally open contact 55 comprised in circuit controller E may be reversed by the engineer by means of a manually operable button 98. In order to cut out the train governing mechanism when entering non-positive control territory, the engineer reverses circuit controller E while the vehicle is receiving energy from the special section L—N. The relative polarity of the current from local transformer 8 of this section is such that relay A is energized in normal direction while the train occupies this section. The closing of contact 55 of circuit controller E closes a primary circuit for relay F, which circuit is from positive

wire 58, through the right-hand point of contact 48, wires 59, 60 and 85, contact 55, wire 86, primary winding 52^P of relay F, wires 87, 72 and 63, right-hand point of contact 49 of relay A, to negative wire 64. The current thus supplied to the primary winding 52^P causes relay J to become energized. As soon as the vehicle passes off of the special section L—N, so that relay A becomes de-energized, the engineer releases circuit controller E, which circuit controller thereupon returns to its normal position, but relay F being already energized, a holding circuit is closed through the secondary winding 52^S of this relay, which holding circuit passes from positive wire 58, through wire 79, back contact 50 of relay A, wires 80 and 81, front point of contact 66 of relay F, wire 88, secondary winding 52^S of relay F, wires 89, 90 and 35, contact 37 of circuit controller E, wires 36 and 29, to negative wire 64. Relay F, therefore, remains energized as long as relay A remains in the de-energized condition.

25 Relay F is a "slow pickup" relay, so constructed that the time taken to close its contacts when winding 52^P is energized is greater than the time taken for relay A to open its contacts 48 and 49 due to cutting resistance R into the local receiving circuit when on a trackway circuit of normal value. Relay F is also made a "slow release" relay, so that when once energized, it will remain picked up after relay A is de-energized for a sufficient time to enable the engineman to restore switch E to normal. The time that relay A becomes de-energized is made evident by the extinguishing of the light 54^H whose circuit is open at contact 48, and 30 by the failure of the lamp 54^R to light because its circuit will be opened when relay F is energized, at back contact 66. All lights of indicator G out, therefore, is a distinctive indication to the engineman that he is in non-positive territory with relay F energized.

45 While the cut-out relay F is energized, brake magnet H is energized by a circuit which passes from positive wire 58, through wire 79, back contact 50 of relay A, wires 80 and 91, front point of contact 67 of relay F, wire 69, magnet H, wire 70, front point of contact 68 of relay F, wires 92, 90 and 35, contact 37 of circuit controller E, and wires 36 and 29, to negative wire 64. The vehicle 50 may, therefore, proceed at full speed without incurring an automatic application of the brakes. When the vehicle again enters positive control territory, that is, territory which is provided with trackway current supplying apparatus, relay A will become energized, thereby opening the holding circuit for relay F, so that the governing mechanism on the vehicle will again be restored to its normal condition wherein this mechanism is controlled in accordance with the energization

of relay A, and again illuminating lamp 54^H or 54^R, and closing back contact 66 so that lamp 54^L may be illuminated when relay A is again de-energized.

It will be observed that the holding circuit for seconding winding 52^S of the cut-out relay F includes contact 37 of circuit controller E, which is the contact that serves to shunt the resistance R. If the engineer reverses the circuit controller E while traveling in non-positive control territory, the opening of contact 37 will introduce resistance R into the holding circuit for relay F, so that this relay will become de-energized. Brake magnet H will thus be de-energized, so that the vehicle cannot exceed the fixed low speed limit without incurring an automatic application of the brakes. In order, therefore, to proceed through non-positive control territory at a speed higher than the fixed low value, it is absolutely essential for the engineer to leave the cut-out circuit controller E in its normal position, and I thus assure that when the vehicle again enters positive control territory resistance R will be cut out to permit relay A to pick up so that relay F will become de-energized, thereby restoring the vehicle governing mechanism to control by the main relay A.

55 Although I have herein shown and described only one form of apparatus embodying my invention, it is understood that various changes and modifications may be made therein within the scope of the appended claims without departing from the spirit and scope of my invention.

Having thus described my invention, what I claim is:

1. Railway vehicle carried apparatus comprising a first front coil mounted in inductive relation to one rail, a second and a third front coil mounted in inductive relation to the other rail, a first and a second rear coil mounted in inductive relation to the first rail, a third rear coil mounted in inductive relation to the second rail, a track receiving circuit, a local receiving circuit, and a circuit controller effective when in normal position to connect the first and second front coils in opposition in the track receiving circuit and the first and third rear coils in series in the local receiving circuit, said circuit controller when in reverse position being effective to connect the second and third rear coils in opposition in the track receiving circuit and said first and third front coils in series in the local receiving circuit.

2. Railway vehicle carried apparatus comprising a first front coil mounted in inductive relation to one rail, a second and a third front coil mounted in inductive relation to the other rail, a first and a second rear coil mounted in inductive relation to the first rail, a third rear coil mounted in inductive relation to the second rail, a track condenser and a local con-

denser, and a circuit controller effective when in normal position to connect the first and second front coils in opposition across the track condenser and the first and third rear coils in multiple across the local condenser, said circuit controller when in reverse position being effective to connect the second and third rear coils in opposition across the track condenser and the first and third front coils in series across the local condenser.

3. Railway vehicle carried apparatus comprising a first front coil mounted in inductive relation to one rail, a second and a third front coil mounted in inductive relation to the other rail, a first and a second rear coil mounted in inductive relation to the first rail, a third rear coil mounted in inductive relation to the second rail, a track condenser and a local condenser, a circuit controller effective when in normal position to connect the first and second front coils in opposition across the track condenser and the first and third rear coils in series across the local condenser, said circuit controller when in reverse position being effective to connect the second and third rear coils in opposition across the track condenser and the first and third front coils in series across the local condenser, a track amplifier having an input circuit connected across said track condenser, and a local amplifier having an input circuit connected across said local condenser.

4. Railway vehicle carried apparatus comprising a receiving circuit including a normally shunted resistance, a main relay controlled by said circuit, a cut-out relay, a pick-up circuit for said cut-out relay including a normally open circuit controller and a contact closed only when said main relay is energized, a stick circuit for said cut-out relay including said resistance, and manually operable means for simultaneously opening the shunt around said resistance and closing said normally open circuit controller.

5. Railway vehicle carried apparatus comprising a circuit receiving energy from the trackway and including a normally shunted resistance, a main relay controlled by said circuit and responsive to the energy normally received therein when said resistance is shunted but not responsive when the shunt around the resistance is removed unless the circuit receives a greater amount of energy from the trackway, a cut-out relay, a pick-up circuit for said cut-out relay including a normally open circuit controller and a contact closed only when said main relay is energized, a stick circuit for said cut-out relay including said resistance whereby said cut-out relay will remain closed only when said resistance is shunted, and manually operable means for simultaneously opening the shunt around said resistance and closing said normally open circuit controller.

6. Railway vehicle carried apparatus com-

prising a circuit receiving energy from the trackway and including a normally shunted resistance, a main relay controlled by said circuit and responsive to the energy normally received therein when said resistance is shunted but not responsive when the shunt around the resistance is removed unless the circuit receives a greater amount of energy from the trackway, a cut-out relay, a pick-up circuit for said cut-out relay including a normally open circuit controller and a contact closed only when said main relay is energized, a stick circuit for said cut-out relay including said resistance whereby said cut-out relay will remain closed only when said resistance is shunted, manually operable means for simultaneously opening the shunt around said resistance and closing said normally open circuit controller, a vehicle governing magnet normally energized only when said main relay is energized, and an auxiliary circuit for said magnet including a contact closed only when said cut-out relay is energized and also including said resistance, whereby said magnet cannot be effectively energized by its auxiliary circuit unless said resistance is shunted.

7. Railway vehicle carried apparatus comprising front and rear receiving coils mounted in inductive relation to the track rails, a normal track receiving circuit including a front coil for one rail and a front coil for the other rail connected in opposition, a normal local receiving circuit including a rear coil for one rail and a rear coil for the other rail connected in series and also including a resistance, a reverse track receiving circuit including a rear coil for one rail and a rear coil for the other rail connected in opposition, a reverse local receiving circuit including a front coil for one rail and a front coil for the other rail connected in series and also including the said resistance, circuit controlling means effective when in normal position to close said normal circuits and effective when in reverse position to close said reverse circuits, and cut-out apparatus controlled by said resistance.

8. Railway vehicle carried apparatus comprising front and rear receiving coil mounted in inductive relation to the track rails, a normal receiving circuit including a rear coil for one rail and a rear coil for the other rail and a resistance, a reverse receiving circuit including a front coil for one rail and a front coil for the other rail and said resistance, circuit controlling means effective when in normal position to close said normal circuit and effective when in reverse position to close said reverse circuit, and cut-out apparatus controlled by said resistance.

9. Railway vehicle carried apparatus comprising a circuit receiving energy from the trackway and including a normally shunted resistance, a main relay controlled by said

circuit and responsive to the energy normally received therein when said resistance is shunted but not responsive when the shunt around the resistance is removed unless the circuit 5 receives a greater amount of energy from the trackway, a cut-out relay, a pick-up circuit for said cut-out relay including a normally open circuit controller and a contact closed only when said main relay is energized, a 10 stick circuit for said cut-out relay including a contact closed only when said main relay is de-energized, and manually operable means for simultaneously opening the shunt around said resistance and closing said normally 15 open circuit controller.

10. Railway vehicle carried apparatus comprising a circuit receiving energy from the trackway and including a normally shunted resistance, a main relay controlled by said circuit and responsive to the energy normally received therein when said resistance is shunted but not responsive when the shunt around the resistance is removed unless the circuit receives a greater amount of energy from the 25 trackway, a cut-out relay having a pick-up winding and a holding winding, a circuit for said pick-up winding including a normally open circuit controller and a contact closed only when said main relay is energized, a circuit for said holding winding including a contact closed only when said main relay is de-energized, and manually operable means for simultaneously opening the shunt around said resistance and closing said normally open 30 circuit controller.

11. Railway vehicle carried apparatus comprising a main relay controlled from the trackway, governing mechanism normally controlled by said relay, a manually operable 40 circuit controller including a normally open contact and a normally closed contact, a cut-out relay, a pick-up circuit for said cut-out relay including said normally open contact and a contact closed only when said main relay is energized, a stick circuit for said cut-out relay including said normally closed contact and a contact closed only when said main relay is de-energized, and means for removing said mechanism from control by said 45 main relay when said cut-out relay is energized.

12. Railway traffic controlling apparatus comprising a main relay controlled from the trackway, a circuit controller having a normal position and manually movable to a reverse position, a cut-out relay, a pick-up circuit for said cut-out relay closed only when said main relay is energized and said circuit controller is in reverse position, a stick circuit for said cut-out relay effective only when the cut-out relay is energized and said main relay is de-energized and said circuit controller is in normal position, vehicle governing mechanism controlled by said main relay, 60 and means for removing said mechanism 65

from control by said main relay when said cut-out relay is energized.

13. In an automatic train control system, the combination with influence receiving coils on the vehicle in inductive communication with the track rails, a main relay maintained energized in response to currents flowing in the track rails through the medium of said coils, a brake control device energized if said main relay is energized, a stick relay which if energized maintains said brake control device energized if said main relay is de-energized, said stick relay having a stick circuit including a front contact of said stick relay and a contact of said main relay closed if said main relay is in its de-energized condition, and means for picking up said stick relay requiring manual intervention and the flow of excess current in the track rails.

In testimony whereof I affix my signature. 85
